METEOROLOGICAL APPARATUS

Ira E. McCabe, Chicago, Ill.

Application October 5, 1942, Serial No. 460,922

8 Claims. (Cl. 177—329)

This invention relates to improvements in meteorological apparatus and more particularly to an instrument or device to be attached to a pilot balloon whereby the travel of the balloon at night will make high altitude upper wind observation possible.

With airplane flying around 20,000 to 30,000 feet high altitude upper wind data looms more important and desirable and in addition is often useful to a weather analyst and forecaster through altitudes of 15,000 to 40,000 feet.

For theodolite night observations candle burning lanterns have been sent aloft by pilot balloons up to 20,000 feet with favorable success, the disadvantage of such forms of light sources, however, being the handling difficulties in preparing for ascent including the assembly of lighted candles, the launching with high surface winds prevailing, and the fire hazard naturally encountered.

As an alternative form of light source, electric bulbs of the auto bulb type have been used with dry cells for this purpose. Success with these has been comparable with the candle type with the advantage of ease in handling and launching regardless of surface winds and the elimination of fire hazard. However, the dry cells lose their efficiency at low temperature below about 5° Fahrenheit (at about 15,000 feet) requiring the use of heat insulation and with the aggregate weight of the lamp and battery unit is sufficient to represent a hazard in falling from several miles altitude when the balloon bursts unless a small parachute is connected thereto.

It is an object of this invention to provide an instrument or device of this character without a parachute combining the efficiency of the candle light type with the lack of hazardous weight of the electric lamp bulb type. It is another object of this invention to provide a device which will be efficient at above 30,000 feet altitude as well as to compensate for the altitude at which the balloon carrying the instrument is released.

With these and other objects in view, reference is made to the accompanying sheets of drawings which illustrate a preferred form of this invention with the understanding that detail changes may be made without departing from the scope thereof.

In the drawings:

Figure 1 is a view in perspective of this invention as assembled in its transportation container with successive parts broken away toward the center showing the exposed elements in elevation.

Figure 2 is a view in perspective of a heating pad.

Figure 3 is a view in perspective of a saturating pad.

Figure 4 is a view in elevation of the liquid receptacles showing one in central vertical section and the means for releasing the contained liquid.

Figure 5 is a top plan view of the envelope containing the liquid receptacles and pads as assembled before the envelope is folded over with parts of the envelope broken away illustrating the relation of the liquid receptacles and pads and also showing the batteries and lamp in their normal position resting upon the bottom of the envelope.

Figure 6 is a view in side elevation of Figure 5 showing the envelope as normally folded over at the center to embrace the batteries and support the lamp.

Figure 7 is a view in perspective of this improved device as attached to a pilot balloon (not shown).

Figure 8 is a view in perspective illustrating the manner in which the necks of the liquid receptacles are broken.

Figure 9 is a detail view of the preferred type of electric lamp bulb in elevation with parts broken away to illustrate the internal construction.

Figure 10 is a view similar to Figure 9 illustrating a modified form of lamp.

Figure 11 is a view in central vertical section through a modified form of liquid receptacle.

As illustrated in Figures 1 to 7, inclusive, this invention contemplates the production of a meteorological instrument to be carried by pilot balloon above 30,000 feet altitude for night observation which employs an electric flasher lamp energized by a two cell dry battery. As the balloon ascends the atmospheric pressure and temperature decrease until the intense cold at extremely high altitudes renders the dry cell battery inoperative and as the flasher lamp is of the mercury tube type, the mercury solidifies. To meet and overcome these conditions, the batteries are not only protected by insulation but a positive source of heat is provided to maintain the batteries in operative condition.

As shown in the drawings, the electric flasher lamp 1 is preferably constructed in accordance with the disclosure in this applicant's co-pending applications, Serial Nos. 440,684 and 440,685, both filed April 27, 1942, which include a pool of mercury 2 with one electrode passing through the sealed end to terminate below the surface of the mercury, which electrode adjacent its lower end supports a capillary tube 4 which presents a meniscus of mercury to be normally engaged by the movable end 5 of the other electrode, the opposite end of which is carried on one end of a strip 6 of bi-metallic metal. The other end of the strip 6 is mounted and connected to one end of the lamp filament 7 which in turn is connected to

the other electrode 8 passing through the seal of the lamp, as shown in Figure 9. As described in said co-pending applications, when the electrodes 3 and 8 are connected in circuit with the source of electricity the completing of the circuit energizes the filament 7. The heat from the glowing filament acts upon the strip 6 to move the end of member 5 out of contact with the meniscus of mercury in the tube 4 to break the circuit through the lamp. The circuit is re-established upon the cooling of the filament 7 so that there is a continuous flashing of the lamp as long as it is connected in series to the source of electricity. It is also preferable to coat the upper surface of the bulb 1 with a light reflecting material 9 to direct the rays of the flash downwardly.

It is also preferable to provide two small dry cell electric batteries 10 and 11 connected in series with each other and with the electrodes 3 and 8 of the lamp. As shown in Figure 5 the lead 12 from electrode 3 is connected to one terminal of the battery 10 and lead 13 from the electrode 8 to one terminal of the battery 11. Lead 14 is connected to the other terminal of battery 10 and is adapted to be connected to the lead 15 connected to the other terminal of battery 11. The leads 14 and 15 are of sufficient length to project beyond the instrument for the purpose hereinafter described.

To insure the operativeness of the batteries 10 and 11 at high altitudes where the low temperature encountered would normally render the batteries inoperative, a source of heat is provided to embrace the batteries. This source of heat includes two heating units 16 and 17, each of which includes a heating pad 18, such as disclosed in patents, Nos. 2,040,406 and 2,040,407 of May 12, 1936, and Nos. 2,208,815 and 2,208,816 of July 23, 1940, containing a chemical enclosed in a foil envelope with one side perforated as at 19, Figure 2, and a similar size pad 20 of absorbing material placed next to the perforated side of the pad 18 and covered upon the opposite side with waxed paper 21 or other liquid impervious material, as shown in Figure 3. When water or anti-freeze liquid is introduced at one end between the pads 18 and 20, the entire surface of the absorbing material of pad 20 becomes moist and the moisture passes through the perforations 19 in the pad 18 to combine with the chemical therein to produce heat.

To provide a source of water or anti-freeze solution for each heating unit, liquid receptacles 22 and 23 are provided for each element, as shown in Figure 4. These receptacles are preferably spherical in shape with a radial filling stem 24 for partially filling with the desired liquid 25 and the filling stem then drawn into a capillary tube 26 and the end tipped off to form an end cap 27. The closure 27 is so formed that it may be detached or the capillary tube fractured by tying one end of a cord 28 about the tube below the cap 27 and exerting a sharp pull upon the cord.

The heating elements 16 and 17 are assembled with the sealed ends of the liquid receptacles 22 and 23 projecting between the pads and the elements which are then inserted through the opposite open ends of a flat tube or envelope 29 of Cellophane or other moisture impervious material so that the liquid receptacles 22 and 23 are adjacent each other but in spaced apart relation with the cord 28 on the outside of the envelope. The ends 30 of the envelope are then sealed.

In assembling the instrument, the batteries 10 and 11 are laid upon one end of the Cellophane envelope 29 adjacent the pad 20 with the lamp 1 projecting therebelow as shown in Figure 5.

- 5 The envelope is then folded over as shown in Figure 6 so that the heating elements 16 and 17 embrace the batteries 10 and 11 with the leads 14 and 15 projecting through and beyond the folded portion and the cord 28 attached to the closures 27 of the liquid receptacles 22 and 23 extending between the pads 18 and 20 of each element and then through the sealed ends 30 of the envelope 29. The folded envelope 29 as shown in Figure 6 is then wrapped in a layer of 10 light weight insulating material 31 such as "Kimsul" which is preferably held in place by ties 32 of thread. The cylindrical package so formed is then inserted in the open end of a cylindrical covering 33 preferably of aluminized Cellophane or other light weight heat insulating material with the open end extending beyond the insulation 31 to the end of the lamp 1 as shown in Figure 7. The leads 14 and 15 are passed through the closed end of the cover 33 and extend there- 15 beyond a sufficient distance to be engaged with each other to form a supporting loop 34.

It is preferable to insert the instrument so assembled into a metal container or casing 35 having a closed end section detachably secured to 30 the casing by means of a sealing strip 36. Into the closed end a spacer 37 is placed having a center opening to receive the bulb 1 and cord 28 to support the bulb in spaced apart relation with the end of the closed section. The leads 35 14 and 15 are disconnected and separated and then coiled about within the opposite open end of the casing 35, whereafter the case is hermetically closed with the end cover 38 providing a sealed safe package for transportation and protection until the instrument is to be used.

When it is desired to use this instrument, the container 35 may be opened by a key 39 to remove the sealing strip 36 and the instrument removed. The insulation about the ends of the 40 leads 14 and 15 is removed and the bare leads joined and twisted about each other to complete the circuit from the batteries 10 and 11 through the lamp 1. The instrument is then reversed as shown in Figure 8 and cord 28 is manually jerked to fracture the capillary tubes 26 by the 45 removal of the closures 27 from the liquid receptacles 22 and 23 between the pads of each heating unit 16 and 17. The instrument is then inverted and attached by the loop 34 formed by the joining of leads 14 and 15 to the support cord 40 of the pilot balloon, not shown.

The air entrapped above the liquid 25 in each of the liquid receptacles 22 and 23, when the closure caps 27 are removed, will be at the same 60 atmospheric pressure as the surrounding air and will vary with the altitude of the place where the balloon is to be released. The removal of the closure caps 27 and the inverting of the instrument will allow the pressure of the entrapped air to force the liquid from the receptacles between the pads of the heating elements 16 and 17 as the balloon ascends and the normal atmospheric pressure decreases thereby generating sufficient heat about the batteries to maintain their operativeness during the observation.

If extremely high altitudes are to be reached for observation where the temperature may be low enough to freeze the mercury 2 in the lamp 1, it is preferable to construct the lamp with an elongated bulb 1a as shown in Figure 10 and

place it in a spherical bulb 41, exhaust the air and then seal the bulb 41 to provide a vacuum therein to insulate the lamp. In such a case the exterior of the bulb 41 may be provided with a reflecting surface 9 to direct the rays of the 5 flasher in a downward direction.

Figure 11 illustrates a modification of the liquid receptacles for wetting the pads of the heating elements 16 and 17 which is automatic in operation and does away with the necessity of 10 the cord 28 hereinbefore described.

In this form a metallic cup shaped vessel is provided with a spring diaphragm which is placed over the opened end of the cup and sealed. The diaphragm supports at its center to extend into the cup a tapered pin, which, when the diaphragm is pressed inwardly past its longitudinal center is caused by a snap action to pass through a hole in alignment therewith in the bottom of the vessel.

By applying pressure to the pointed pin protruding from the bottom of the vessel the diaphragm can be flexed so as to snap the pin out from the hole, thus permitting the filling of the vessel with a desired amount of liquid whereafter the diaphragm is flexed downwardly to close the hole. A small amount of wax may be applied to completely seal around the hole.

In utilizing this form of liquid receptacle a short piece of rubber or some other water resistant tubing may serve to conduct the released liquid to the absorbent pad 20.

In operation, as the balloon ascends, the lowering of atmospheric pressure will result in the pressure within the vessel forcing the diaphragm upwardly breaking the wax seal and gradually opening the hole until with the snap of the diaphragm it is completely opened. The liquid charge and point of operation can be easily established at the time of manufacture by the degree of vacuum established within the vessel for filling purposes.

An instrument as described and illustrated in Figure 7 has been produced which weighs 3½ ounces and has been successfully tested to maintain the batteries in operative position to flash the lamp during conditions which correspond to 60 minutes of flight to an altitude of 42,000 feet.

While the flasher type lamp has been disclosed herein as the preferred form of lamp to be used in such an instrument, a constant burning lamp such as the auto type previously referred to may be employed without departing from the scope of this invention.

What I claim is:

1. A means protecting dry cell electric batteries from excessive cold in meteorological instruments carried by a pilot balloon for excessive high altitude observation, said instrument including an electric lamp operated by a dry cell battery, including heat producing pads rendered active upon the application of moisture placed about said battery, and a source of moisture associated with each pad provided with automatic means for progressively releasing the moisture from said source to said pad as the altitude increases.

2. The structure of claim 1 wherein said source of moisture includes partially filled liquid containers, each provided with breakable seals whereby upon the breaking of the seals the surrounding atmospheric pressure normally maintains the liquid within the containers and as

the atmospheric pressure decreases as the altitude increases the decreasing pressure allows the internal pressure within the containers to progressively discharge the liquid therefrom upon the heating pads.

3. The structure of claim 1 wherein said source of moisture includes partially filled liquid containers each provided with a discharge port, a diaphragm operated valve normally closing said ports responsive to atmospheric pressure to open as the altitude increases to allow the internal atmospheric pressure within the containers to discharge the contained liquid upon the heating pads.

4. In a signal lamp for high altitude observation, an insulated electric battery and heating unit having an electric lamp extending exteriorly from the bottom thereof, wires extending exteriorly from the top of said unit adapted to be joined together to complete in a series circuit the battery and said lamp and in addition to provide a means of attachment to a pilot balloon, said heating unit comprising moisture operative chemical heating pads arranged adjacent the battery to impart heat thereto, liquid containers provided with means to discharge the liquid contained therein upon lowering atmospheric pressure to wet and cause the activation of the heating pad chemical, said pads and containers being sealed within a moisture proof container being sealed within a moisture proof envelope.

5. The structure of claim 4 wherein the liquid containers are partially filled with liquid sealed therein with breakable seals, said liquid being subjected to the prevailing atmospheric pressure upon breaking the seal to prevent the discharge of liquid therefrom until lower atmospheric pressure conditions are established and means operable from without the insulated unit to break the seals.

6. The structure of claim 4 wherein the liquid containers are partially filled with liquid sealed therein with breakable seals, said liquid being subjected to the prevailing atmospheric pressure upon breaking the seal to prevent the discharge of liquid therefrom until lower atmospheric pressure conditions are established and means operable from without the insulated unit to break the seals and means for conducting the discharged liquid over the surface of the heating pad and insulating the absorbing surface of the pad from the moisture proof envelope.

7. The structure of claim 4 wherein the liquid containers are provided with a discharge port normally closed by a resilient diaphragm actuated member under high atmospheric pressure, said diaphragm under low atmospheric pressure flexed by the internal pressure within the container to open the port for the discharge of the liquid therefrom.

8. The structure of claim 4 wherein the liquid containers are provided with a discharge port normally closed by a resilient diaphragm actuated member under high atmospheric pressure, said diaphragm under low atmospheric pressure flexed by the internal pressure within the container to open the port for the discharge of the liquid therefrom, means for conducting the discharged liquid over the surface of the heating pad and insulating the absorbing surface of the pad from the moisture proof envelope.
